UNITED STATES PATENT OFFICE.

FRANK O. MITTAG, OF PARK RIDGE, NEW JERSEY.

BOAT.

1,295,784.

Specification of Letters Patent. Patented Feb. 25, 1919.

Application filed November 19, 1917. Serial No. 202,709.

To all whom it may concern:

Be it known that I, FRANK O. MITTAG, a citizen of the United States, and a resident of Park Ridge, in the county of Bergen and

5 State of New Jersey, have invented certain new and useful Improvements in Boats, of which the following is a specification.

The invention resides in a novel type and construction of power-driven boat.

10 One object of the invention is to provide a boat of very staunch construction and capable of attaining a high speed. A further object of the invention is the production of a high speed boat which will ride 15 steadily through and to a large extent on or over the surface of the water and have no tendency to turn over. Another purpose of the invention is the production of a boat which although comparatively wide and 20 long may be turned or deflected from its course quickly and within a short space.

In carrying out my invention I make the hull of the boat comparatively wide, as distinguished from the narrow sharp-pointed 25 types of high-speed boats, and except for a curved bow my boat presents, preferably, when viewed in top elevation, an oblong outline, the longitudinal lines of the sides of the hull being parallel and straight and 30 the transverse line of the stern being straight. The bow portion of my boat is of special construction in that it is preferably convexly curved along its upper forward lines, that its bottom extends downwardly 35 and rearwardly and more particularly that said bottom is formed with two plain side sections of comparatively narrow width and between said sections with a wide downwardly and rearwardly extending concave 40 section which starts at the bow and finally merges into the lines of the main bottom of the boat. My construction of bow results in the forward portion of the boat riding up out of the water when the boat is in motion, 45 thereby minimizing friction and resistance, and also in the boat riding steadily and safely. In rear of the bow I provide the bottom of my boat with a number of vertical fins or blades arranged longitudinally and 50 in staggered order and these fins or blades aid in steadyng the boat and facilitate the short-turning or deflection of the same. I also preferably provide horizontal fins or plates at the opposite sides of the rear end 55 of the boat and close down to the bottom of the boat. The propeller-shafts issue

through the bottom of the boat and the propellers are preferably below the rear end of the boat and are submerged when the boat is in use.

60 The invention will be fully understood from the detailed description hereinafter presented, reference being had to the accompanying drawings, in which:

Figure 1 is a top view of a boat constructed in accordance with and embodying the invention;

Fig. 2 is a bottom view of the same;

Fig. 3 is a side elevation of the same;

Fig. 4 is a vertical transverse section, on 70 a larger scale, through the same taken on the dotted line 4-4 of Fig. 3;

Fig. 5 is a like section through the same taken on the dotted line 5-5 of Fig. 3;

Fig. 6 is a top view, partly broken away, 75 of the interior framing within the forward portion of the boat;

Fig. 7 is a view partly in section and partly broken away and partly in side elevation of a portion of the rear part of the 80 boat, the section being on the dotted line 7-7 of Fig. 5;

Fig. 8 is a front elevation, partly broken away, of the interior framing at the bow of the boat, and

85 Fig. 9 is a front elevation of the boat.

In the drawings, 10 designates the opposite sides of the boat, 11 the bow, 12 the stern, 13 the usual steering wheel, 14 the rudder, 15 the engines, 16 the propeller 90 shafts, 17 the propellers on the rear ends of said shafts, 18 fins or blades secured to the bottom 19 of the boat, 20 lateral fins or plates secured to the sides of the stern of the boat and in near relation to the bottom 95 thereof, 21 a compartment having seats 22 for passengers or crew, and 23 a compartment having a seat 24 for passengers or persons using the boat.

The sides 10 are preferably parallel and 100 straight, and the stern 12 is transverse and preferably straight.

The bow 11 is covered over or has a deck 25, and the upper front portion of said bow is on convex lines, as shown.

105 The bottom construction of the bow of the boat is of special importance, and said bottom extends downwardly and rearwardly and comprises two side sections 26 and a concave section 27 (Figs. 2 and 9), which is 110 between and wider than the sections 26. The sections 26 curve downwardly and rear-

wardly and merge into the flat bottom 19 of the boat, and the concave section 27 starts well up at the front of the bow and extends downwardly and rearwardly and finally 5 merges into said bottom 19.

- 10 The bottom 19 connects the sides 10 and extends rearwardly from the bow-sections 26, 27, and said bottom has a raised or offset section 28 below the stern of the boat, whereby there is formed a space into which the propeller shafts 16 may project, as shown in Figs. 2 and 3, and carry the propellers 17 wholly below the stern of the boat.
- 15 The bottom 19, including its section 28, has the longitudinal elongated vertical fins or blades 18 secured thereto, there being three rows of said fins or blades, in staggered relation, on the main portion of said 20 bottom and two rows of said fins on said section 28.

I have found the fins or blades 18 to be of considerable importance in a boat of the construction presented by me, in that they 25 aid in steadyng the boat and keeping it on its course and also permit of the turning of the boat within a short space. The fins 18 on the upwardly offset portion 28 of the bottom of the boat are particularly useful 30 in a boat of my construction, because when this boat is in use the bow rides upwardly and the stern to a certain extent submerges, and at this time the fins 18 on said bottom section 28 act to steady the stern of the boat 35 and aid in guiding the boat on its course. The laterally projecting fins or plates 20 secured to the opposite sides of the stern of the boat and near the bottom thereof co-operate with the general construction of the 40 boat in avoiding rocking of the boat and also co-operate with the fins 18 in facilitating the keeping of the boat on a straight course or on such course as may be imparted to it from the rudder.

- 45 The interior of the boat is composed of staunch framing to which the outer planking or covering is applied, and in Figs. 4 and 8 I indicate the interior framing of the bow portion of the boat, this construction 50 being also to a certain extent indicated by dotted lines in Figs. 1 and 3. In the interior of the bow portion of the boat I provide a series of upper and lower transverse beams numbered, respectively, 29, 30 whose outline 55 is represented in Figs. 4 and 8. The beams 29, 30 are secured at their ends to vertical beams 31 and at their middle portions they are connected by vertical beams 32, said beams 31, 32 varying in length from the 60 extreme bow portion of the boat toward the compartment 21. The vertical beams 31, 32 are connected together wherever convenient and possible by crossed timbers 33 (Fig. 4). The upper and lower beams 29, 30 65 are, adjacent to the beams 31, connected

together by vertical beams 34, and these beams 34 are connected together by longitudinally extending beams 35. I also connect the vertical beams 31 by means of longitudinal beams or bars 36, and from the short 70 forward vertical beam 32 (Fig. 8) I extend brace beams 37 which, as indicated by dotted lines in Fig. 1, are secured to and diverge rearwardly from the said forward vertical beam 32 and at their rear ends are 75 secured to the vertical beams 34. The construction just described may vary, but it is one which has proven to be desirable and results in a bow construction of very strong 80 and durable character and capable of withstanding the treatment to which it is subjected when the boat is in actual use. I preferably arch the upper beams 29, and the lower beams 30 are concaved in their middle 85 portions so as to create the bottom side sections 26 and bottom concave section 27, which portions, as hereinbefore described, extend downwardly and rearwardly to about in line with the front end of the compartment 21.

90 The interior structure of those portions of the boat at the rear of the bow portion may vary but preferably will comprise vertical bars or ribs 38, transverse beams 39, longitudinal beams 40 set upon said transverse 95 beams 39, and angularly set braces 41 extending downwardly and inwardly from the vertical members 38 to the transverse beams 39 and secured to said vertical and transverse members, as shown in Fig. 5. The 100 braces 41 are preferably mortised in the vertical beams 38 and on the transverse beams 39 and bear upon the longitudinal timbers or beams 40. I also, as shown at the right hand side of Fig. 6, employ additional longitudinal, transverse, diverging and vertical members, but these need not be specifically explained since they may vary with the determination or will of the builder of the boat. 105 My boat is of special exterior outline, and I 110 have described the essential portions of the skeleton frame to receive the outer planking and establish said outline.

115 My invention will be largely understood from the foregoing description so that further detailed explanation is not required. I may again mention, however, that when the boat is in use and driven by high power so as to create speed, the bow of the boat rides upwardly in the water, due to the construction of the bow portion of the boat, while the stern of the boat partly submerges, so that the propellers are entirely below the water line. I have found that the exterior 120 shape of this boat and its special bottom construction contribute to high efficiency and that the boat constructed as described may employ engines 15 of high H. P.

125 Among the purposes I have accomplished in my construction of boat is the attainment 130

of high speed, steady and safe riding, and capability of short turning or deflection within limited space. My construction of boat also permits me to use engines of high 5 H. P. and to minimize friction and resistance, all this being true even though the boat of my invention is comparatively broad as distinguished from high speed boats having sharp pointed bows and which otherwise 10 lack the characteristics of my boat.

What I claim as my invention and desire to secure by Letters-Patent, is:

1. A boat of the character described having parallel vertical sides from bow to stern, 15 a substantially straight stern, a slightly forwardly arched bow-line, a main flat bottom and a bow portion which extends downwardly and rearwardly and comprises two parallel flat side sections and an upwardly 20 concaved intermediate section and which sections merge into the flat bottom of the boat adjacent to the bow portion of the boat, and which boat is provided at its stern with propelling means.
- 25 2. A boat of the character described having parallel vertical sides from bow to stern, a substantially straight stern, a slightly forwardly arched bow-line, a main flat bottom and a bow portion which extends downwardly and rearwardly and comprises two 30 parallel flat side sections and an upwardly

concaved intermediate section and which sections merge into the flat bottom of the boat adjacent to the bow portion of the boat, and which boat is provided at its stern with propelling means, said flat bottom having at the stern of the boat an upwardly offset section, and said propelling means comprising propellers which with their shafts are below 35 said upwardly offset section of the bottom. 40

3. A boat of the character described having parallel vertical sides from bow to stern, a substantially straight stern, a slightly forwardly arched bow-line, a main flat bottom and a bow portion which extends downwardly and rearwardly and comprises two parallel flat side sections and an upwardly concaved intermediate section and which sections merge into the flat bottom of the boat adjacent to the bow portion of the boat, and 45 which boat is provided at its stern with propelling means, said flat bottom in rear of said bow portion having a series of vertical fins spaced apart both longitudinally and transversely considered. 50 55

Signed at New York, in the county of New York and State of New York, this 15th day of November, A. D. 1917.

FRANK O. MITTAG.
